[57] **CLAIM**

The ornamental design for a high pressure hot liquid cleaning apparatus, as shown and described.

DESCRIPTION

FIG. 1 is an isometric view of a high pressure hot liquid cleaning apparatus embodying the design;

FIG. 2 is a front elevational view thereof;

FIG. 3 is a rear elevational view thereof;

FIG. 4 is a right end elevational view thereof;

FIG. 5 is a left end elevational view thereof;

FIG. 6 is a top plan view thereof; and

FIG. 7 is a bottom plan view thereof.

FIG. 1

FIG. 2

FIG. 3

FIG. 4

FIG. 5

FIG. 6

FIG. 7
